The ornamental design for a housing of a micro puree machine, as shown and described.

DESCRIPTION

FIG. 1 is a top, front and right side perspective view of a housing of a micro puree machine of our new design;

FIG. 2 is a left side elevation view thereof;

FIG. 3 is a right side elevation view thereof;

FIG. 4 is a front elevation view thereof;

FIG. 5 is a rear elevation view thereof;

FIG. 6 is a top plan view thereof; and,

FIG. 7 is a bottom plan view thereof.

In the drawings, the broken lines depict portions of the housing of the micro puree machine and form no part of the claimed design.

1 Claim, 5 Drawing Sheets**Related U.S. Application Data**

continuation-in-part of application No. 18/089,689, filed on Dec. 28, 2022, now Pat. No. 11,819,814, and a continuation-in-part of application No. 17/992,263, filed on Nov. 22, 2022, now Pat. No. 11,759,057, which is a continuation of application No. PCT/CN2022/123016, filed on Sep. 30, 2022.
